UNITED STATES PATENT OFFICE

WILLIAM LOTT MILLER, OF WINONA, MINNESOTA

INSULATING SLAB

Application filed June 14, 1930. Serial No. 461,231.

My invention relates to insulating slabs and particularly to such structures as are adapted to be installed within a wall, partition or other structure to be insulated.

5 An object of the invention resides in providing an insulating slab which may be placed on edge and which may be constructed with a body formed of a loosely packed fibrous material such as mineral wool or any 10 type of organic fibrous material.

Another object of the invention resides in preventing the body of the slab from settling or otherwise moving when installed on edge so as to prevent the formation of an unfilled 15 space at the upper end of the body.

A still further object of the invention resides in providing a keeper for engaging portions of the body of the slab to hold the same intact.

20 A feature of the invention resides in constructing said keeper with a supporting member having means thereon for engaging the body at various separate localities for preventing relative movement of the portions of 25 the body so engaged.

An object of the invention resides in constructing said member planiform and in disposing the same parallel to one of the surfaces of the slab.

29 Another object of the invention resides in providing said member with prongs issuing outwardly therefrom and extending into the fibers of the body.

A still further object of the invention resides in imbedding the keeper within material 35 of the body of the slab.

A feature of the invention resides in disposing said prongs on both sides of said planiform member to more effectively engage the material of said body.

An object of the invention resides in constructing said prongs so that the same will resist movement of various portions of the body of said slab in one direction.

43 Another object of the invention resides in constructing said prongs so that the same will resist movement of the various portions of the body of the slab in several directions.

A still further object of the invention resides in constructing said member in the form

of a supporting sheet and in providing prongs issuing outwardly therefrom, some of said prongs being able to resist stresses in one direction and other of said prongs being able to resist stresses in another direction. 55

A feature of the invention resides in providing a wall along which said body extends and in arranging said prongs so as to extend toward said wall, said prongs falling short 60 of said wall.

An object of the invention resides in providing a case for said body having spaced parallel walls, and in arranging within said body prongs extending toward both of said 65 walls, said prongs falling short of both of said walls.

Another object of the invention resides in completely imbedding the prongs and the supporting structure therefore within said body. 70

Other objects of the invention reside in the novel combination and arrangement of parts and in the details of construction hereinafter illustrated and/or described. 75

In the drawings:

Fig. 1 is a perspective view of an insulating slab with portions thereof cut away to show the interior construction of said slab and illustrating an embodiment of my invention. 80

Fig. 2 is a perspective view of the keeper used with the form of the invention shown in Fig. 1 and drawn to a larger scale than that employed in Fig. 1. 85

Fig. 3 is an enlarged cross sectional view taken on line 3—3 of Fig. 1.

Fig. 4 is a perspective view of another form of keeper.

Fig. 5 is a cross sectional view taken on line 5—5 of Fig. 4. 90

Fig. 6 is a perspective view similar to Fig. 1 illustrating a modification of the invention.

Fig. 7 is a perspective view of still another form of keeper similar to that shown in Fig. 1. 95

Fig. 8 is a cross sectional view similar to Fig. 3 and showing another form of the invention.

Fig. 9 is a cross sectional view similar to Fig. 8 and showing the method of applying 100

the prongs to the structure illustrated in Fig. 8.

Figs. 10 and 11 are cross sectional views similar to Fig. 5 and illustrating modified forms of keepers.

In the insulation of refrigerators, refrigerating rooms and various types of buildings, it has been customary to construct the walls and partitions of such structures with inner 10 and outer sheathing and in disposing between such sheathing insulating material of some sort or other. A convenient method has been to construct the insulating material in the form of slabs and to insert these slabs into 15 the space between the sheathing of the walls or the partitions during the construction of the same. In the construction of such slabs it has been attempted to employ a case of some suitable material and to dispose within 20 said case a body formed of some suitable organic fibrous substance. Such construction, however, has been found to be highly impractical due to the fact that some of the slabs are placed on end and settling of the 25 material forming the body of such slabs would leave a vacant space at the upper end of the slab devoid of insulating material. Such uninsulated space within the slabs greatly cuts down the efficiency of the insulation 30 and renders such construction practically useless for the desired purpose. The present invention provides a construction whereby such settling of the body of the slab is prevented so that complete insulation is had 35 throughout the entire extent of the slab.

In the form of the invention shown in the drawings, the insulated slab has been illustrated as contained within a case indicated in its entirety at 15. In instances where the 40 slab is constructed at the locality where the refrigerator or other wall to be insulated is being constructed, this case may be dispensed with and the insulated slab disposed directly in between the sheathing of the wall. However, where the slab is built at one locality and the refrigerator or wall wherein the 45 same is used is at another locality, the case 15 is highly preferable, and for this reason, all of the forms of the invention are 50 shown as contained within such a case. The case 15 is preferably constructed from a strip of cardboard or other suitable material 16 which is of a width equal to the thickness of the slab to be formed and which is bent in a 55 rectangle as best shown in Fig. 1 to extend about the four edges of the finished slab. In the construction of the slab this strip is disposed about a suitable form and a sheet of paper or other suitable material such as indicated at 17 placed along one edge of the 60 strip 16 and folded over and attached to said strip as by gluing, stapling, or otherwise. The body of the slab which is indicated at 18 is next placed within the interior of the case 65 15 and the same closed through another sheet

of paper 19 which is laid over the other edge of the strip 16 and secured to the same. In this manner the body 18 is completely concealed along all surfaces thereof and the shape thereof retained within the strip 16 and the sheets of paper 17 and 19 overlying the same. If desired, the strip 16 and the body 18 may be wrapped in a single sheet of paper folded about the same and secured in place by any suitable means.

In conjunction with the body 18, I employ a keeper 20 a portion of which is shown in detail in Fig. 2. This keeper may be constructed of certain types of paper which may be readily punched and bent to give sufficient rigidity to serve the desired purpose. In the formation of the keeper 20, the stock or sheet of paper from which the same is constructed is punched to form two series of prongs 21 and 22 which extend outwardly 70 from the sheet in opposite directions therefrom. In use, the keeper 20 is imbedded within the interior of the body 18 of the insulating slab so that the prongs 21 and 22 thereof extend into the body on both sides 75 of said sheet and hold the same intact. In the formation of the prongs 21 and 22, the sheet from which the keeper 20 is formed is severed along two parallel lines 23 and 24 and along a diagonal line connecting these 80 parallel lines so that the two prongs 21 and 22 extend outwardly from the same opening. By means of this construction the prongs may be more closely situated relative to one another than where one prong is struck out from 85 each hole. In the construction of the prongs in this manner, it will be noted that each prong is formed with an edge 25 at right angles to the surface of the sheet and with an edge 26 inclining relative thereto. When the 90 prongs engage into the body 18 of the slab, the edges 25 operate more effectively to prevent the shifting of the material from which the body is constructed than the edges 26. For this reason, the positions of the edges 95 25 of the respective prongs vary as best shown in Fig. 2 so that some of the prongs resist shifting of the body 18 in one direction and other of said prongs resist the shifting 100 of said body in other directions. When the slab is properly constructed with the keeper 105 20 imbedded within the same, said slab may be placed on edge and some of the prongs thereof will have their edges 25 operating to restrain shifting of the body 18 with respect 110 to the case 15. This is true regardless of what edge of the slab the same is made to rest upon since the prongs are arranged alternately to 115 present the perpendicular edge thereof either in an upward or downward direction or in a right hand or left hand direction and to either 120 side of the sheet. If desired, the keeper 20 may be constructed of metal or any other suitable substance from which prongs such as 125 shown can be punched and formed.

In the construction of the slab shown in Fig. 1, the case 15 is constructed as previously described with the sheet 17 secured to the strip 16. An amount of fibrous material sufficient to form one-half of the thickness of the body 18 is then laid within said case and upon the sheet 17. The keeper 20 is next placed upon the sheet and pressed into the same sufficiently to cause the various prongs 21 issuing outwardly therefrom to enter into said body and become firmly lodged therein. Another amount of fibrous material indicated at 28 and sufficient to form the other half of the body 18 is thereafter placed upon the keeper 20 and the same pressed into the prongs 21 issuing outwardly from the other side of said keeper. The case is then closed through the sheet 19 which is glued or otherwise secured to the strip 16. The slab is then complete and can be shipped and handled without danger of the body thereof being shifted and without danger of the same settling when installed into the structure in which the slab is to be used. Where an extra thick slab is desired or where further support is required than possible with the structure shown in Fig. 1, several keepers such as shown may be employed and distributed in spaced parallel formation in the slab with layers of the insulating material therebetween. By means of this construction slabs of any thickness or any proportions may be constructed.

In Fig. 4, I have shown another form of keeper which is indicated in its entirety at 29 which may be used in place of the keeper 20 shown in Fig. 2. This keeper consists of a sheet of paper or cardboard 30 which has attached to it at various localities covering the entire surface of said sheet a number of wire staples 31 and 32. These staples may be attached to the sheet as shown in Fig. 5 and are provided with offset portions 33 which hold said staples firmly secured to the sheet. It can readily be comprehended that these staples are most capable of resisting pressure applied in a plane containing the legs 34 and 35 thereof. For this reason some of the staples, namely those indicated at 32, are arranged to extend in one direction while the other staples indicated at 31 are arranged to extend in a direction at right angles thereto. Furthermore some of each of the staples extend through the sheet in opposite directions so that there are staples on both sides of the sheet extending in two directions. When the keeper 29 is used in conjunction with a slab such as indicated in Fig. 1, the slab may be placed on any of the edges thereof and the various staples 31 and 32 serve to hold the body of the slab in proper position the same as the prongs 21 and 22 of the form of keeper shown in Fig. 2.

If desired, the staples used in conjunction with the keeper 29 may be secured to the

paper by the forming of the offsets in the opposite direction from that shown in Fig. 5 as illustrated in Fig. 10. In this form of the invention, the sheet to which the staples are attached is designated at 36 while the staples are indicated at 37. It will be noted that offsets 38 are formed on said staples which clinch the staples securely to the sheet 36 and that said offsets extend in the opposite directions from the offsets 33 in Fig. 5. This construction brings the protruding ends 39 and 40 closer to one another than the ends 36 and 37 of the other structure, otherwise the keeper shown in Fig. 10 operates identically the same as that shown in Fig. 5.

Where a fairly stiff heavy paper is used, the staples may be attached to the same without the use of the offset portions such as indicated at 33 or 38 to clinch the staples in place. Fig. 11 shows a structure having the staples so attached. In this figure the paper or sheet to which the staples are attached is designated at 41 and the staples are indicated at 42. The staples are partially held in place through frictional engagement with the sheet 41 while the pressure of the body of the slab against the staples further assists in holding the staples in place and prevents the fibrous material from being disengaged therefrom.

In Fig. 7, I have shown a different form of keeper which may be constructed from paper or sheet metal and in which the prongs issuing outwardly therefrom which are designated at 43 may be constructed somewhat differently than the prongs 21 and 22 of the form of the invention shown in Fig. 2. In the construction of these prongs, one prong is struck out from each opening in the sheet and said prong is formed triangular and is bent along a medial line 44 to provide two portions 45 and 46 issuing outwardly from the sheet at right angles to the sheet. These portions of the prong are capable of resisting stresses in two directions so that one of the prongs 43 takes the place of two of the prongs 21 shown in the other form of the invention. The various prongs 43 are alternately disposed upon the opposite sides of the sheet to provide means for engaging the body on both sides of the sheet and said prongs are also arranged in inverted order so as to resist strains either in an up and down or in a left and right hand direction.

Where the slab is designed for a particular installation in which the same is at all times to remain in a given vertical position, it is not necessary to provide prongs for resisting stresses in more than one direction. A slab particularly adapted to such use is shown in Fig. 6. This slab comprises a case 47 identical with the case 15 of the form of the invention shown in Fig. 1 and further includes a body 48 of fibrous material identical with the body 18. Instead of using a

keeper such as shown in conjunction with the device illustrated in Fig. 1, a number of vertical strips 49 are employed which are imbedded within the body 48 and are spaced 5 from one another. These strips have attached to them staples 50 and 51 which extend through said strips in opposite directions. These staples may be attached to said strips as shown in Figs. 5, 10 or 11. In the drawings, said staples have been illustrated as attached to the strips by the method shown in Fig. 11 due to the fact that where the individual strips 49 are employed the same are preferably constructed of heavier material than where an entire sheet such as shown in Fig. 4 is employed which would not require the rigid fastening necessary with a thinner supporting member.

In Figs. 8 and 9 I have shown a still different form of keeper for the invention. In this figure a case 52 is employed identical with or similar to the case 15, and a body 53 is employed of fibrous material similar to the body 18. Within this body may be disposed a keeper indicated at 54 which may be constructed of a sheet such as shown in Fig. 4 at 30 or a number of strips such as illustrated at 49 in Fig. 6. The prongs used with this form of the invention consist of pins 55 which extend through the sheet or strips forming the supporting structure for the keeper 54 and fall short of both the front and rear surfaces of the slab. These pins may be inserted into the slab after the sheet or strips constituting the supporting structure for the keeper 54 has been placed within the same. This is accomplished by compressing the surface of the body 53 as indicated at 56 in Fig. 9 which upon being released immediately springs to its normal shape and completely encloses the various pins. The pins 55 may be inserted before the outer sheet 57 of the case 52 has been applied to the same as illustrated in Fig. 9 or said pins may be caused to penetrate said sheet of the case to be applied to the device after the slab has been completely encased. Where a relatively firm and rigid material is used for the sheet supporting the pins 55, said pins may be attached to the sheet before the same is imbedded in the slab.

Although I have shown but one form of case for encasing the slab, it can readily be comprehended that any suitable box structure 55 for holding the same in place may be employed or that the slab without case may be directly placed into the compartment in which it is to be used without departing from the spirit of the invention. It can also be readily comprehended that other forms of keepers and different types of prongs may be employed all within the scope of the invention. It is also not absolutely necessary to have the keeper parallel to the walls of the slab so long as the supports carried thereby

are distributed about the material constituting the body of the slab, and the supporting structure of the keeper need not necessarily be confined to a plane or single surface but may be zig-zagged or corrugated or may be formed of individual strips arranged in angular or parallel relation to one another.

My invention is highly meritorious in that an extremely simple and effective structure is provided whereby insulating slabs may be constructed of fibrous material at considerable less expense than where constructed of other substances. Settling or shifting of the material from which the body of the slab is constructed is completely prevented. The keepers used with the invention may be constructed to prevent shifting of the body of the slab in one or more directions as the occasion demands. The keepers can be constructed at a nominal cost and operate in a positive and effective manner. The prongs may be applied to one or both of the sheets forming the side walls of the case for the slab or the same may be mounted on a separate sheet or strips imbedded within the body of the slab proper. In the construction of the invention the prongs are arranged so as to extend only partially through the body of the slab thereby preventing conductance of heat from one surface of the slab to the other through the agency of said prongs and further preventing sweating.

Changes in the specific form of the invention, as herein disclosed, may be made within the scope of what is claimed without departing from the spirit of my invention.

Having described my invention, what I claim as new and desire to protect by Letters Patent is:

1. An insulating slab comprising a body formed of a loosely packed fibrous material, a supporting sheet parallel to one of the surfaces of said body, prongs issuing outwardly from said sheet for independently supporting portions of said body at various localities when said slab is placed on one edge, and other prongs issuing outwardly from said sheet for independently supporting portions of said body at various localities when said body is arranged on another edge.

2. An insulating slab comprising a body formed of a loosely packed fibrous material, a supporting sheet imbedded within said body and parallel to one of the surfaces thereof, and prongs issuing outwardly from said sheet from opposite sides thereof to engage said body at various localities therein.

3. An insulating slab comprising a case formed with spaced parallel walls, a body of loosely packed fibrous material disposed between said walls, a supporting sheet disposed within said body and spaced from said walls, said sheet having prongs issuing outwardly therefrom and entering into said body, said

prongs falling short of all of the walls of said case.

4. An insulating slab comprising a body formed of a loosely packed fibrous material, a supporting sheet parallel to one of the surfaces of said body, a plurality of prongs issuing from said sheet, bendable relative to said sheet in one direction and rigid with respect thereto in the opposite direction, and a plurality of other prongs bendable with respect to said sheet in the direction in which said first named prongs are rigid and rigid with respect to said sheet in the direction in which said first named prongs are bendable.

15 5. An insulating slab comprising a body formed of a loosely packed fibrous material, a supporting sheet parallel to one of the surfaces of said body, prongs struck out from said sheet and bendable along parallel lines, other prongs struck out from said sheet and bendable along other lines lying at right angles to the first named lines.

6. An insulating slab comprising a body formed of a loosely packed fibrous material, a supporting sheet parallel to one of the surfaces of said body, a plurality of staples having the prongs thereof extending through said sheet with the connecting portions thereof lying parallel to one another and a plurality of other staples having the prongs thereof extending through the sheet and the connecting portions thereof extending at right angles to the connecting portions of said first named staples.

35 7. An insulating slab comprising a body formed of a loosely packed fibrous material, a supporting sheet parallel to one of the surfaces of said body, said sheet being constructed of cardboard and having prongs struck out from said sheet and bendable along parallel lines, other prongs struck out from said sheet and bendable along other lines lying at right angles to the first named lines.

8. An insulating slab comprising a case, a body within said case formed of a loosely packed fibrous material, a readily bendable supporting sheet having rigidity in any direction in the plane thereof, and imbedded within the fibrous material, and prongs struck out of said sheet and extending from both sides of the sheet, said prongs being rigid in one direction to lend support to the fibrous material, some of said prongs on each side of

the sheet being arranged to lend support to the body when the slab rests upon one edge and other of said prongs on both sides of the sheet being arranged to lend support to the body when the slab rests upon another edge, said prongs all falling short of the sides of the case.

9. A slab of insulating material comprising a case, a body within said case formed of a loosely packed fibrous material, a supporting sheet imbedded within the fibrous material, members carried by said sheet and extending toward the side walls of said case for preventing sliding movement of the fibrous material on both sides of the sheet and along the sheet in any direction, said sheet and members being wholly free from the side walls of said case and being carried by the body of fibrous material.

10. A slab of insulating material comprising a supporting sheet, a body of fibrous material arranged in two parts, one on each side of said supporting sheet, means on said supporting sheet issuing outwardly from the surfaces thereof for restraining movement of both parts of the body in the plane of said sheet and in any direction, and a case enveloping said body, said case having sides overlying the parts of the body and ends connected to the sides and operating in conjunction therewith to restrain movement of the parts of the body away from said sheet and to hold the parts of the body in contact with the restraining means on the sheet.

11. A slab of insulating material comprising a supporting sheet, a body of fibrous material overlying said supporting sheet, means on said supporting sheet issuing outwardly from the surface thereof on which said body is disposed and entering into said body for restraining movement of said body in the plane of the sheet and in any direction and a case including a sheet overlying said body and further including marginal portions bent from said sheet and overlying the edges of the slab, said marginal portions being substantially immovable relative to said first named sheet and serving to hold the body in engagement with the restraining means thereon.

In testimony whereof I have affixed my signature.

WILLIAM LOTT MILLER.
